CLAIM

The ornamental design for a jet ski carrier, as shown and described.

DESCRIPTION

FIG. 1 is a front perspective view of a jet ski carrier.
FIG. 2 is a rear perspective view of a jet ski carrier.
FIG. 3 is a front elevation view of the jet ski carrier.
FIG. 4 is a rear elevation view of the jet ski carrier.
FIG. 5 is a top plan elevation view of the jet ski carrier.
FIG. 6 is a bottom plan elevation view of the jet ski carrier.
FIG. 7 is a left side elevation view of the jet ski carrier; and,
FIG. 8 is a right side elevation view of the jet ski carrier.
